J. R. Cornwall.

ATTY.

UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

TRUSSED BRAKE-BEAM.

1,219,436.

Specification of Letters Patent. Patented Mar. 20, 1917.

Application filed August 11, 1916. Serial No. 114,422.

To all whom it may concern:

Be it known that I, EDWIN G. BUSSE, a citizen of the United States, residing at the city of Chicago, county of Cook, and State 5 of Illinois, have invented a certain new and useful Improvement in Trussed Brake-Beams, of which the following is a full, clear, and exact description, such as will enable others skilled in the art to which it 10 appertains to make and use the same, reference being had to the accompanying drawings, forming part of this specification.

This invention relates broadly to railway rolling stock and specifically to certain im- 15 provements in the construction of trussed brake beams.

In the employment of forged struts in trussed beams, experience has demonstrated that the modicum of flexibility which the 20 forged strut possesses sometimes permits a displacement of the strut with reference to the compression member of the beam, such displacement being due, no doubt, to the springing of the strut when the brake lever 25 is operated with excessive violence, and an unequal bearing of the brake heads at the opposite ends of the beam against the re- spective wheels.

The object of my present invention resides 30 in the provision of a brake beam construction wherein means is supplied for effectively clamping the strut to the compression member in such fashion as to prevent movement of the former relative to the latter, 35 and yet in such fashion that the parts may be freed from each other if desired, or the clamping engagement may be tightened if desired.

In the accompanying drawings, illustra- 40 tive forms of my invention are disclosed,

Figure 1 representing a side view of a strut showing the compression member in section;

Fig. 2, a sectional view showing the com- 45 pression member and clamping parts partly in cross section; and

Fig. 3 a similar section of a modified form.

Referring to these illustrations by means 50 of the reference characters applied, let it be understood that 1 indicates the compression member of the brake beam, that shown be- ing in the form of a rolled channel, though other forms, of course, may be used, and 2 55 represents the body portion of the strut. In

the forged strut illustrated in Figs. 1 and 2, this body portion is in the nature of a band or strap which is bent upon itself to form a seat for the compression member, and the end portions being disposed parallel 60 and spaced apart for the reception of the brake lever, and being deflected to the proper angle to support the brake lever in the customary position. At the forward end of the body member is supported a seat 65 member 4 which is formed to engage the tension member of the beam, and also to form a spacer between the end portions of the body member 2.

Adjacent the compression end of the strut, 70 a block 5 is interposed between the con- joined portions of the body member, forming a spacer between the said portions and formed to accommodate the rivet or the fastening means 6. This block projects rear- 75 wardly into the seat portion of the strut, but, of course, terminates short of the walls of the seat portion sufficiently to give the proper space for the compression member. It has the upwardly and downwardly pro- 80 jecting bearing portions 5^a which are adapt- ed to coöperate with the inner faces of the flanges of the compression member, and the rearward end of this block member 5 is 85 countersunk or apertured to form a seat or housing for a movable clamping block 7, and the portions forming the lateral walls of said housing are apertured to form key- 90 ways adapted for the reception of a wedge key 8 which, upon movement longitudinally through the apertures and in engagement with the clamping block 7, will wedge the latter outwardly or toward the rear wall of the compression member seat. In this 95 operation the clamping block is retained against movement transversely of the strut or longitudinally of the compression mem- ber by the walls of the countersunk seat portion. Hence, the clamping action will be exerted directly against the web of the 100 compression member in line with the axis of the strut, and the clamping block will be securely retained against accidental dis- placement. In assembling the beam, the strut is slipped over the end of the com- 105 pression member and slid longitudinally thereon until the proper position at the center is reached. Then the wedge key is driven inwardly, forcing the clamping block 7 rear- wardly into engagement with the web por- 110

tion of the compression member. The rear wall of the compression member seat, of course, coöperates with the clamping block 7 to closely clamp the web of the compression member, so that the strut is held securely against longitudinal movement upon the compression member. If it becomes necessary to tighten this clamping engagement it may be easily accomplished by driving 10 the wedge key farther into the block, and if it becomes desirable to remove the strut, the latter may be unclamped from the compression member by simply removing the wedge key.

15 In the modification illustrated in Fig. 3, the strut is a cast member instead of a forged member, and the block 5' which forms a seat for the clamping block, is cast as an integral part of the strut.

20 I am aware that the invention is not limited to the specific embodiments herein shown and described, and it is, therefore, my intention that the appended claims be construed to cover all the various possible 25 modifications and adaptations.

What I claim is:

1. In a brake beam, a longitudinal member and a strut formed with a seat for the reception of the longitudinal member, said 30 strut being provided with a block portion extending into said seat, a movable clamping member supported on said block, and means coöperating with the block and clamping member whereby the latter may be forced into clamping engagement with the longitudinal member within the seat.
2. In a brake beam, a longitudinal member and a strut member formed with a seat for the reception of the longitudinal member; said strut member including a block 40 portion extending into the seat and spaced apart from the walls thereof, a movable clamping member carried on the block member and retained thereby against movement longitudinally of the longitudinal member, and means operable to urge the clamping member toward the longitudinal member.
3. In a brake beam, a longitudinal mem-

ber and a transverse strut member formed 50 with a seat portion for the reception of the longitudinal member; said strut member including a block portion extending into said seat and having portions arranged to engage the flanges of the longitudinal member and a clamping member movable on the longitudinal axis of the strut and arranged for adjustable clamping engagement with the longitudinal member.

4. In a brake beam, a truss member and 60 a strut member formed with a seat portion adapted for the reception of the truss member; said strut member including a block portion and a movable clamping member supported thereby for clamping coöperation 65 with an opposite side of the seat portion; the block portion carrying means for retaining the clamping member against movement longitudinally of the truss member; and a member movable longitudinally 70 of the truss member to effect clamping engagement of the clamping member and truss member.

5. In a brake beam, a longitudinal member, and a strut member having a seat portion 75 adapted for the reception of the longitudinal member; said strut member having an adjustable clamping portion operable within the seat portion for engagement with the longitudinal member and means for retaining said clamping member against movement away from the longitudinal axis of the strut member.

6. In a brake beam, a longitudinal member, and a strut member formed with a terminal seat for the reception of the longitudinal member; a spacing block mounted between the sides of the strut member, and a movable clamping device secured thereon and coöperating with the seat portion to engage the longitudinal member.

In testimony whereof I hereunto affix my signature in the presence of two witnesses this 8th day of August, 1916.

EDWIN G. BUSSE.
